LABORATORY DRYING OVEN

Sigvard Frans August Ekelund, Brandeborg,
Ljungbyhed, Sweden

Application November 20, 1950, Serial No. 196,611

Claims priority, application Sweden
November 21, 1949

4 Claims. (Cl. 34—48)

1 In drying ovens for laboratory use of the hitherto customary type the inconvenience is frequently caused that when inserting the material to be dried in the oven, a temperature drop occurs, the recovery from which takes a relatively long time and which in addition must be regarded as undesirable for drying many samples. These conditions are encountered both in drying ovens of the kind in which air constitutes the chief heat accumulating and heat conducting mass, and in ovens with heat accumulating masses of a liquid kind. The latter possess the further disadvantage that they must be kept filled with a certain quantity of liquid, such as water, and that it is scarcely possible to construct them in such a way that the receptacle containing the material to be dried comes into satisfactory contact with the water without the material being affected by steam.

The present invention relates to a drying oven for laboratories of the type which is heated up by means of a source of heat to a temperature suitable for drying preparations, such as 100° C., and the invention has for its purpose to provide a drying oven which, without being unduly bulky, possesses a sufficiently large capacity for accumulating heat to prevent the temperature from falling appreciably when inserting the material to be dried and which is also so constructed that the accumulated heat can be rapidly transmitted to the material to be dried.

According to the invention the drying oven is mainly characterized by the fact that it contains a solid body of a heat-accumulating and heat-conducting material which is of such preponderating magnitude in relation to the quantity of material to be dried and the bulk of the container for the sample that the drop of temperature on the insertion of the container with the sample is negligible, 5° C. max. for example, preferably below 1° C., whilst the space or spaces provided in the drying oven for the material to be dried, the drying chambers, are formed in such a manner that the heat of the said heat-accumulating body is rapidly transmitted to the material to be dried, for example by constructing the drying chambers with small dimensions and with a form adapted to the type of container or dish for the samples usually employed with a ground bottom. Preferably the drying oven is provided with a plurality of separate drying chambers each of which communicates through passages with the outside of the oven.

As suitable materials for the heat-accumulating body may be mentioned metals and metal

alloys, such as iron, copper, brass and aluminum. It is not necessary that the whole heat-accumulating body is constructed of the same material, and it may consist of two or more different metals, for example. The source of heat for heating the drying oven may be of any desired type and may preferably be electric heating elements, and it should be adapted primarily in relation to the total heat losses of the drying oven caused by radiation and convection.

2 The heat-accumulating body must be adequately insulated on the outside, by making its surface bright, for example, and by surrounding it with a layer of glass wool, ceramic material or other suitable heat insulating material. It is also possible to enclose the whole of the body or oven in an evacuated vessel, such as a vacuum container. On the other hand, surfaces of the body turned towards the drying spaces may be made black or dull so that heat radiation is facilitated. Each separate drying chamber should be provided with a special closing device such as a cover, a door or the like, and this cover, etc. must naturally be formed in a manner similar to that of the body in other respects, so that the heat will be applied to the material to be dried as uniformly as possible from all sides.

The passages through which the separate drying chambers communicate with the outside of the oven should be so arranged that the air or gases circulating through the passages, if such are employed, will flow over as large a surface of the material to be dried as possible and as close to the said surface as is permissible with respect to the type of material to be dried. Preferably, the passages, or the inlet passages at least, should run substantially vertically through the body so that a natural circulation of pre-heated air or gas will consequently pass over the material to be dried. On the outer sides of the body the passages should open into sleeves or valves so that the flow can be regulated and arrangements connected up for the absorption of moisture, suction, measuring the volume of gas, etc. It should also be possible to draw or pump air or gas in series through two or more of the different spaces, if necessary, after the intermediate connection of absorption devices, and also for carrying out drying with a regulated circulation and with regulated temperature, pressure and moisture of the circulating medium. The closing devices for the separate drying chambers must, of course, permit perfectly tight closure under such conditions.

In consequence of the fact that the drying oven is provided with a plurality of separate drying chambers, the samples of materials present in the drying oven are not affected when a sample of an entirely different kind is inserted in the oven. According to the invention possibilities are also provided for ventilating the drying chambers individually. Thus, the position of a sample in the drying oven does not affect the possibilities of controlling said sample.

In order that the invention may be clearly understood it will now be described more fully with reference to the accompanying drawings in which by way of example preferred forms are illustrated.

Fig. 1 shows schematically a vertical section through a drying oven which may be a part of a larger oven with a plurality of drying spaces or chambers;

Fig. 2 is a vertical section through a drying oven with a plurality of drying spaces or chambers arranged in a common body of a heat-accumulating material, taken along the line II-II of Fig. 3;

Fig. 3 is a view of the drying oven of Fig. 2, seen from above; and

Fig. 4 illustrates schematically different manners of application of the drying oven according to Figs. 2 and 3.

In Fig. 1, 1 is a body of a heat-accumulating material, i. e. of high specific heat such as iron, in which is arranged a hollow space 2 opening at one side of the body 1 for receiving a drawer 5 which can be inserted in said space from the side 5 which can be inserted in said space from the side of the oven. The body 1 has a bright outer surface 3 and is externally insulated by means of a layer 4 of a suitable ceramic material, glass wool or the like. The drawer 5 has a massive outer part 6 made of the same material as the body 1 and is at the outside provided with an insulating layer 7, similar to the layer 4, with a handle 8. The inner part 9 of the drawer is of a material having a large heat conducting capacity, such as copper or brass. In said inner part 9 is arranged a hollow space or recess for receiving a container or dish 10, which may preferably be of aluminum or other metal with high heat conductivity, in which the sample of material 11 to be dried (the drying goods) is placed. In order to secure the best possible contact between the surface of the recess and the outer surface of the dish 10 and, consequently, the most favourable heat transmission to the drying goods, the form of the dish should be such that it fits closely to the internal contour of the recess, and suitably said surfaces are flat-ground.

When the drawer 5 is in the position shown in the drawing, the inner part 9 thereof is in close contact with an inner body 12 inserted in a hollow space in the main body 1 of the drying oven. This body 12 consists, like the inner part 9 of the drawer, of a material having large heat conducting capacity, for example copper or brass. Said body 12 and the inner part 9 of the drawer 5 completely surround and limit the drying chamber 2' of the oven. The body 12 is provided with a depending flange or extension 12' which like a root projects into the lower part of the body 1, thus surrounding a heating element 13 which is inserted in a cavity in the body 1. For regulating said heating element a thermostat 14 is provided, as indicated in the drawing. The insulating layer 4 may be provided with a protective casing, for example of sheet metal with a bright outer surface.

The drying chamber 2' is connected to an inlet passage 15 for supplying air or other gaseous medium for the drying which extends from the underside of the oven to one edge of the chamber 2', and to an outlet passage 16 for the escape of moist air or gas from the chamber which extends from the opposite edge of the chamber 2' to the upper side of the oven. Owing to the location of these passages circulation is ensured over the greatest possible surface of the material 11 to be dried, and this effect is further increased by the fact that the part of the body 12 forming a roof of the drying chamber is made convex as indicated by 17 in the drawing.

15 Suitably, the electric heating element 13 may be so dimensioned that its effect only slightly exceeds what is required for maintaining the body 1, when already heated to a desired predetermined range of temperature, within said temperature range, with regard to the losses of heat to the surroundings and to the drying goods. In this case the heating of the drying oven to this temperature range at the beginning of the drying process, or before, may be effected by means of an extra heating source, for example a spiritus burner, or by placing the oven on an electric heating plate. After the desired temperature has been reached, the necessary heat is supplied by means of the element 13 and the thermostat 14.

The drying oven shown in Figs. 2 and 3 contains six separate drying chambers 20, each of which is accessible from the upper side of the oven through a cover consisting of a part 21 of an insulating material and a body 22 of a heat accumulating material, for example iron. The main part of the oven consists of a body 23 of a heat accumulating material, such as iron, through which channels 24 pass from below to the drying chambers and channels 25 therefrom upwards, as in case of the oven in Fig. 1. The body 23 has a bright outer surface and is externally insulated by means of a layer 33 of a suitable insulating material, such as a ceramic material, glass wall or the like. Said insulating layer 33 may be surrounded by a protective casing, for example of sheet metal with a bright outer surface. The cover body parts 22 are at their underside made convex in order to narrow the passage and increase the contact between the circulating gas and the surface of the drying goods.

In the body 23 is, in similar manner as described in connection with Fig. 1, inserted an inner body 26 of a material possessing good heat conducting capacity, for example copper or brass. This body 26 is provided with rootlike projections 26' projecting downwards into the body 23, and crownlike projections 26'' directed upwardly. These crownlike projections 26'', together with linings 27 of the same or a similar material provided at the underside of the cover body parts 22, surround the drying chambers 20. A thermometer 28 is inserted in the centre of the oven.

In a cavity 29 in the lower central part of the body 23 are provided two electric heating elements, namely an element 30 of greater effect for the primary heating of the oven to the desired drying temperature range, and a separate electric element 32 regulated by means of a thermostat 31, for maintaining as far as possible a constant temperature of the body 23 and in the oven. In comparison with the element 30, the element 32 has a very low effect.

As already mentioned, each of the six drying chambers 20 is connected with the outside of

the drying oven by means of channels 24 and 25 respectively, and the cover bodies 22 are preferably flat-ground in such a manner that they fit completely vacuum-tight to the adjacent contacting surfaces, which are preferably also flat-ground. Hereby the oven is adapted for application in many different manners at normal pressure or in vacuum, as is schematically illustrated in Fig. 4. Each drying chamber may be used independently of the other chambers, or two or several drying chambers may be connected in series and used for the same drying purpose.

In Fig. 4, the drying chamber, designated DC I, is assumed to be applied for drying a sample of material in the usual manner, in the presence of air, passing through the channels 24 and 25. The next drying chamber, DC II, is applied for drying in an atmosphere of nitrogen supplied from a gas container 34 through a moisture absorbent 35 and a valve 36 in the channel 24 in such a way that the gas is forced to pass through the drying goods and then escape through the channel 25.

In the next drying chamber, DC III, the sample to be treated is assumed to contain micro-organisms and these are killed by first treating the material with steam from a boiler 31, whereupon, by turning the valve 36, dry air is supplied and circulated through the drying chamber after passing the moisture absorbent 35. The next drying chamber, DC IV, has its outlet channel 25 connected to a vacuum pump 38 for evacuating the drying chamber and hereby the inlet chamber 24 is closed by the aid of the valve 36. Afterwards the valve 36 is turned for supplying dried and purified air passing through a U-shaped tube 36, containing suitable chemicals, with the inlet valve 40.

The two remaining drying chambers, DC V and DC VI, are connected in series by means of a conduit containing a moisture absorbent apparatus 35 and a valve 36, the same arrangements being also provided in the inlet passage to the chamber DC VI. For supplying a regulated quantity of air to the drying chambers the outlet passage from the drying chamber DC V is connected with a gas volume meter 41 and also with a pump 42 which draws a quantity of air controlled by the meter 41 through the two drying chambers.

In many cases it may also be advantageous to connect the outlet passage from the drying chamber with a moisture absorbent apparatus which makes it possible to control the loss of weight of the sample as well as the increase of weight of the absorbent apparatus.

Consequently, as indicated above, the different drying chambers in the oven of Figs. 2 and 3 may be simultaneously applied for quite different drying purposes and drying processes which are carried out independently without disturbing each other.

The drying oven according to the invention may be employed for drying samples of all kinds of solid, semi-solid and liquid materials as are now dried in the customary drying ovens of the air, gas or vacuum types.

As a comparative example of the advantages connected with the use of different metals in the drying oven according to the invention the following data may be given:

A sample of 3 grs. containing 1 gr. water and having a content of solids of 2 grs. is dried in an aluminium dish weighing 20 grs.

	G. Cal.
For heating 2 grs. of dried solids from 20° C. to 100° C. is required about 2.0.3.80	50
5 For heating 1 gr. water from 20° to 100° C. is required	80
For evaporation of 1 g. water at 100° C. is required	540
10 For heating 20 grs. aluminium is required 20.0.22.80=ca.	350
	1020

Consequently totally about 1 kg. cal. is required.

The quantity of different metals required as 15 heat accumulating material, assuming a drop of the temperature in the oven of at most 1° C. after the equilibrium has been restored after supply of heat to the oven, is per sample as follows:

20	Fe	Al	Mg	Cu	% Fe+½ Cu
Weight in kgs.	8.85	4.61	4.03	10.75	9.19
Volume in dm. ³	1.13	1.71	2.32	1.21	1.14
Required height for a piece of 1 dm. ³ surface in cms.	11.3	17.1	23.2	12.1	11.4
25 Heat conductibility: height	0.012	0.029	0.016	0.074	

Especially favourable values are underlined.

30 As appears from the last column, the combination of iron with its high specific heat and copper with its high heat conductivity is especially advantageous, particularly when constructing the oven as shown in the drawings.

35 Although the invention above has been described with reference to preferred constructional forms of the oven, it is obvious that the invention is not limited hereto, since many alterations and modifications concerning the form, size, arrangement of the parts and the material may be made without departing from the scope of the invention.

I claim:

1. A drying oven of the type used for treating 45 test samples in open containers, which comprises in combination a compact metal body having a high specific heat and a high heat conductivity, insulating material surrounding said body, at least one cavity in said body completely enclosed

50 by the metal adapted to receive a container holding a test sample to be treated, said cavity having a bottom and sides conforming in shape to and closely fitting the said container to facilitate heat conduction from said body to said container and

55 to said test sample, closure means comprising part of said metal body for closing off a passage-way providing access to said cavity, and means for heating said body to the treating temperature mounted substantially centrally in said body;

60 said heating means comprising a main electric heating element of high heating capacity adapted to rapidly heat the metal body to operating temperatures and a thermostatically regulated electric heating element adjacent said main heating element having a smaller heating capacity but sufficient to control the temperature of the metal body at the operating point; said metal body having a total heat capacity substantially larger than that of said test sample and container to minimize temperature changes upon introduction of an unheated test sample into said cavity.

65 70 75 2. The drying oven of claim 1 wherein said compact metallic body is constructed of two different metals one having a higher heat conductivity than the other, the said cavity being lined

with the metal of higher heat conductivity, the metal lining having at least one depending extension passing into the second metal and adapted to conduct heat from said heating means to said cavity.

3. A drying oven of the type used for treating test samples in open containers, which comprises in combination a compact metallic body having a high specific heat and a high heat conductivity, said body being made in two interfitting parts 10 of different metals one of which has a higher heat conductivity than the other, at least one cavity in the metal part of higher heat conductivity adapted to receive a container holding a test sample to be treated, said cavity having a 15 bottom ground to fit the test sample container to facilitate heat conduction to the container and to the sample contained therein, means for heating said metallic body located substantially centrally in said body, said metal part of higher heat conductivity having a depending part extending close to said heating means to expedite transfer of heat from said heating means to said container, and ventilating conduits leading to and from said cavity through said metallic body, 25 said metallic body having a total heat capacity substantially larger than that of said test sample and container to minimize temperature changes upon introduction of an unheated test sample into said cavity.

4. A drying oven of the type used for treating test samples in open containers, which comprises in combination a compact metallic block formed in two interfitting parts one of which has a higher heat conductivity than the other, insulating material surrounding said metallic block, a plurality of cavities formed in the top of said metallic block adapted to receive containers with test

samples therein, said cavities being surrounded with said metal of higher heat conductivity, having bottoms conforming in shape and closely fitting the said containers to facilitate heat conduction from said metallic body to said container and test samples, means for heating said metallic block mounted substantially centrally therein, said part of higher heat conductivity having at least one depending extension leading from a point close to said heating means to the metal surrounding said cavities to facilitate transfer of heat from said heating means to the containers and test samples in said cavities, and individual ventilating conduits leading to and from each of said cavities, the metallic block having a substantially larger heat capacity than that of the containers and test samples to minimize temperature changes upon introduction of unheated test samples into said cavities.
